US00D547296S

(12) **United States Design Patent** (10) **Patent No.:** **US D547,296 S**
(45) **Date of Patent:** **** Jul. 24, 2007**

(54) **MOBILE PHONE**

(75) Inventor: **Shih-Ming Lin**, Hsinchu (TW)

(73) Assignee: **Quanta Computer Inc.**, Tao Yuan Shien (TW)

(**) Term: **14 Years**

(21) Appl. No.: **29/258,162**

(22) Filed: **Apr. 18, 2006**

(51) **LOC (8) Cl.** **14-03**

(52) **U.S. Cl.** **D14/138**

(58) **Field of Classification Search** **D14/137, D14/138, 147, 218, 341-347, 496; 455/90.3, 455/556.1, 556.2, 575.1, 575.3, 575.4; 379/433.01-433.13; 361/814; 348/14.02**

See application file for complete search history.
